3 Claims. (Cl. 323—89)

This invention relates to operational amplifiers, and more particularly it relates to a new magnetic operational amplifier.

It is an object of the present invention to solve certain problems associated with conventional magnetic operational amplifiers as will be described in greater detail hereinafter.

It is another object of the invention to provide a new operational amplifier utilizing a magnetic amplifier and exhibiting, without using a high amplification factor, highly desirable characteristics which are equivalent to those obtainable in the case of an operational amplifier having an extremely high amplification factor.

The nature of the invention, its details, and the manner in which the foregoing objects as well as other objects and advantages as will presently become apparent will be fully understood by reference to the following description of a conventional operational amplifier, presented for comparison purpose, and an embodiment of the present invention when taken in conjunction with the accompanying drawing in which like parts are designated by like reference letters, and in which:

FIG. 1 is an electrical connection diagram representing a general example of a conventional operational circuit;

FIG. 2 is a graphical representation indicating characteristic curves of the circuit of FIG. 1; and

FIG. 3 is an electrical connection diagram representing an illustrative embodiment of the operational amplifier according to the present invention.

The connection diagram shown in FIG. 1 represents a conventional feedback operational circuit wherein a magnetic operational amplifier MA is used. This amplifier MA is composed of an alternating-current power source E_s , diodes d_1 , d_2 , d_3 , and d_4 which form a full-wave rectifying circuit, output windings N_1 and N_2 which are wound on separate magnetic cores, and a control coil N_{c1} which is wound commonly on the said magnetic cores. The feedback operational circuit is formed by connecting an input impedance Z_1 and a feedback impedance Z_f to the aforementioned amplifier MA. Reference letter Z_L represents the load of the said circuit.

In such a feedback operational circuit as described above, the input current I_{c1} flowing through the control coil N_{c1} of the operational amplifier MA may be represented by the following equation.

$$I_{c1} = \frac{E_i + E_o}{Z_i + Z_f} \quad (1)$$

where:

Z_1 is the impedance of the winding N_{c1} ;

E_i is the input voltage; and

E_o is the output voltage.

If the amplification factor of the magnetic amplifier itself is denoted by $-R_A$, a voltage which is $-R_A$ times the input current I_{c1} should, conceptionally, appear as the output voltage E_o . Actually, however, the output voltage E_o is as follows:

$$E_o = E_s - E_t \quad (2)$$

where:

E_t is the terminal voltage of the operational amplifier;

and

E_s is the voltage of the alternating-current power source.

The relation between the above said terminal voltage E_t and the load current I , when graphically represented with the input current I_{c1} as a parameter, produces such characteristic curves as are shown by dotted lines in FIG. 2. By considering these dotted line curves to be approximated by the full lines shown, and denoting their slope by $\Delta E_t / \Delta I = Z_0$, the following expression is obtained.

$$E_t = E_R + IZ_0 \quad (3)$$

In the above equation, the value of the voltage E_R is determined by only the magnitude of the input current I_{c1} and may be considered to be given by

$$E_R = I_{c1} R_A$$

As a result, from the foregoing Equations 1, 2, and 3, the following expression for the output voltage E_o can be derived.

$$E_o = E_s - IZ_0 - I_{c1}R_A = E_s - \frac{Z_0}{Z_L} E_o - \frac{\frac{E_i + Z_0}{Z_i + Z_f}}{1 + Z_i \left(\frac{1}{Z_i} + \frac{1}{Z_f} \right)} R_A =$$

$$- \frac{Z_i \left(1 + \frac{Z_1}{Z_i} + \frac{Z_1}{Z_f} \right)}{Z_i + Z_f} \frac{E_i}{R_A} - \frac{E_s}{1 + \frac{Z_i \left(1 + \frac{Z_1}{Z_i} + \frac{Z_1}{Z_f} \right)}{Z_L R_A} (Z_L + Z_0)} \quad (4)$$

In this case, since the power source voltage E_s is a constant voltage, if it is caused to be cancelled by such a suitable means as a push-pull connection, the expression of the Equation 4 will become that of the following equation.

$$E_o = - \frac{Z_f}{Z_i} \frac{E_i}{1 + \frac{Z_i \left(1 + \frac{Z_1}{Z_i} + \frac{Z_1}{Z_f} \right)}{Z_L R_A} (Z_L + Z_0)} \quad (5)$$

The second term in the denominator of the righthand side of the above Equation 5, that is,

$$\frac{Z_i \left(1 + \frac{Z_1}{Z_i} + \frac{Z_1}{Z_f} \right)}{Z_L R_A} (Z_L + Z_0)$$

is an error term. If this term is made to be zero, the output voltage may be expressed by

$$E_o = - \frac{Z_f}{Z_i} E_i \quad (6)$$

whereby an ideal feedback operational circuit can be obtained. For this purpose, the above-mentioned term can be made to approach zero by increasing to an extreme magnitude the amplification factor R_A of the aforesaid operational amplifier. To increase R_A to an extreme magnitude, however, is difficult.

The above problem has been solved by the present invention, in which a voltage compensating winding through which a feedback current which is proportional to the output voltage flows and a current compensating winding through which a feedback current which is proportional to the output current are separately wound, together with a control winding about the magnetic cores of a magnetic operational amplifier, whereby the aforesaid error term can be made to approach zero with

ample proximity without increasing the amplification factor R_A to a substantially large magnitude.

One illustrative embodiment of the operational amplifier according to the invention is shown in FIG. 3, where reference letter R_f designates an output voltage feedback resistance connected in series to a voltage compensating winding N_{c2} , which, together with a current compensating winding N_{c3} , is wound on the magnetic cores C_1 and C_2 of a magnetic operational amplifier. The other parts of this embodiment are the same as those of the conventional amplifier shown in FIG. 1.

The ratio of winding turns of each of the compensating windings N_{c2} and N_{c3} to the winding turns of the control winding N_{c1} may be denoted as follows:

$$\frac{N_{c2}}{N_{c1}} = \beta, \quad \frac{N_{c3}}{N_{c1}} = \alpha \quad (7)$$

Then, the output voltage E_o and the input current I_{c1} may be expressed by the following equations.

$$\left. \begin{aligned} E_o &= -IZ_0 - \left(I_{c1} - \beta \frac{E_o}{R_f} - \alpha I \right) R_A \\ I_{c1} &= \frac{E_i + E_o}{Z_i + Z_f} \end{aligned} \right\} \quad (8)$$

From Equations 8, the following expression for the output voltage E_o is obtained.

$$E_o = \frac{Z_f}{Z_i} \frac{E_i}{1 - \frac{Z_f}{R_f} \left(1 + \frac{Z_i}{Z_f} + \frac{Z_i}{Z_i} \right) \beta + \frac{Z_i \left(1 + \frac{Z_i}{Z_i} + \frac{Z_i}{Z_f} \right) (Z_0 + Z_L - \alpha R_A)}{Z_L R_A}} \quad (9)$$

In the above case, it will be assumed that E_s has been cancelled out.

If now the turn ratio α is so selected as to satisfy the equation $Z_0 = \alpha R_A$, the third term of the denominator of the righthand side of the Equation 9 will become

$$\frac{Z_i}{R_A} \left(1 + \frac{Z_i}{Z_i} + \frac{Z_i}{Z_f} \right)$$

and E_o will become independent of Z_L . Then, if the turn ratio β is so selected as to satisfy the relation

$$\frac{1}{R_A} = \frac{\beta}{R_f}$$

the sum of the second and third term in the denominator will become zero, and the relation expressed in the Equation 6 is obtained.

That is, in the operational amplifier according to this invention, it is possible, by suitably selecting the number of turns of two specially provided, compensating windings, to obtain characteristics which are equivalent to those obtainable in the case wherein an operational amplifier having an extremely high amplification factor is used, even if the amplification factor of the operational amplifier of this invention is not very high.

The operational amplifier of this invention has the further advantage in that the circuit constant of each compensating winding can be determined irrespectively of the values of the load Z_L , the input impedance Z_i , and the feedback impedance Z_f .

Although this invention has been described with respect to a particular embodiment thereof, it is not to be so limited as changes and modifications may be made therein which are within the full intended scope of the invention, as defined by the appended claims.

What is claimed is:

1. A feedback type operational circuit utilizing a magnetic amplifier, which comprises, in combination, an amplifier having two magnetic cores and including an alternating current source; one output winding wound about each said core and connected in parallel to said current source and in series to two diodes which also are connected to said current source; and a control coil wound commonly about said cores; said current source, cores,

diodes, output windings and control coil constituting a full-wave rectifying circuit; a voltage compensating winding and a current compensating winding, both wound about said magnetic cores; an output voltage feedback resistance connected in series to said compensating windings; said voltage compensating winding forming a positive feedback circuit by supplying a current proportionate to a voltage E_o ; an input impedance Z_i connected to a feedback impedance in said current and voltage compensating windings; an input voltage E_i thus being conducted into said control coil; a feedback impedance Z_f being connected to said output and said control winding thus conducting said output voltage E_o thereto; whereby

$$E_o = \frac{Z_f}{Z_i} E_i$$

2. A feedback operational circuit utilizing a magnetic amplifier, which comprises, in combination, an amplifier having two magnetic cores and including an alternating current source; one output winding wound about each said core and connected in parallel to said current source and in series to two diodes which also are connected to said current source; and a control coil wound commonly about said magnetic cores; said current source, cores, diodes, output windings and control coil constituting a full-wave rectifying circuit through whose output windings an output voltage E_o passes, proportionate to the current passing through said control coil; a voltage compensating winding and a current compensating winding, both wound about

said magnetic cores; an output voltage feedback resistance connected in series to said compensating windings; said voltage compensating winding supplying said output voltage E_o ; an input impedance Z_i connected to said current and voltage compensating windings, an input voltage E_i thus being conducted into said control coil; a feedback impedance Z_f being connected to said output and said control winding thus conducting said output voltage E_o thereto; whereby

$$E_o = \frac{Z_f}{Z_i} E_i$$

3. In a feedback type operational circuit utilizing a magnetic amplifier having magnetic cores; an alternating current source; two diodes connected to each said amplifier and to said current source; one output winding wound about each said core and connected in parallel to said current source and in series to said diodes; and a control coil wound commonly about said cores; said amplifier constituting a full-wave amplifying circuit; the improvements which comprise, in combination, a voltage compensating winding and a current compensating winding, both wound about said magnetic cores; an output voltage feedback resistance connected in series to said compensating windings; said voltage compensating winding forming a positive feedback circuit by supplying a current proportionate to a voltage E_o ; an input impedance Z_i connected to said feedback and to said current and voltage compensating windings; an input voltage E_i thus being conducted into said control coil; a feedback impedance Z_f being connected to said control winding thus conducting said output voltage E_o thereto; whereby

$$E_o = \frac{Z_f}{Z_i} E_i$$
